DEVICE FOR CONTROLLING THE HEAT OF INTERNAL COMBUSTION MOTORS

Filed April 21, 1923

UNITED STATES PATENT OFFICE.

JOSEPH O. FORGETTE AND RICHARD LEGOIS, OF HARTFORD, WISCONSIN.

DEVICE FOR CONTROLLING THE HEAT OF INTERNAL-COMBUSTION MOTORS.

Application filed April 21, 1923. Serial No. 633,792.

To all whom it may concern:

Be it known that we, JOSEPH O. FORGETTE and RICHARD LEGOIS, both citizens of the United States, and residents of Hartford, in the county of Washington and State of Wisconsin, have invented a new and useful Improvement in Devices for Controlling the Heat of Internal-Combustion Motors, of which the following is a full, clear, and exact description.

Our invention relates to improvements in devices for controlling the heat of an internal combustion motor, and it consists in the combinations, constructions, and arrangements herein described and claimed.

An object of our invention is to provide a device for controlling the heat of a motor which is manually controlled, and is adapted to be instantly set so as to keep the heat of the engine at the desired temperature.

A further object of our invention is to provide a device of the type described which accurately controls the temperature of the engine, whereby devices for controlling the flow of air into the radiator, such as a cardboard placed in the front of the radiator, are done away with.

A further object of our invention is to provide a device of the type described which is adapted to prevent air from passing over the motor when the car is moving, whereby the heat of the motor will not be dissipated.

A further object of our invention is to provide a device of the type described which can be readily attached to an ordinary automobile engine, and which is adapted to take the place of the fan that is normally used for cooling the radiator.

A further object of our invention is to provide a device of the type described which is simple in construction, durable and efficient for the purpose intended, and which is not likely to easily get out of order.

Other objects and advantages will appear in the following specification, and the novel features of the invention will be particularly pointed out in the appended claims.

Our invention is illustrated in the accompanying drawings forming part of this application, in which—

Figure 1 is a vertical section through the device, portions thereof being shown in elevation, and

Figure 2 is a front elevation of the device. In carrying out our invention, we make use of an engine 1 which has a crank shaft

2 and a fan carrying shaft 3. We apply the device to the shaft 3, the device taking the place of the fan which is usually carried by the shaft. The device consists of a pulley 4 which is mounted upon a hub 5 that is rotatably carried by the shaft 3. Thrust bearings 6 take up the end play of the pulley 4. The crank shaft 2 has a pulley 7 which is operatively connected to the pulley 4 by means of a belt 8. It will be noted from this construction that when the engine is running, it will rotate the pulley 4.

The pulley 4 carries propeller blades 9 which have their shafts 10 rotatably disposed on the pulley. The pulley has a recess 11 into which the inner ends of the shafts 10 project. The blades 9 will be swung when the shafts 10 are rocked. The means for rocking the shafts 10 consists of arms 12, which are readily secured to the shafts 10 that have their free ends operatively connected to a ring 13. The ring 13 is provided with slots 14, into which the free ends 15 of the arms 12 are slidably disposed.

Movement of the ring will cause the arms 12 to swing the blades 9. The means for moving the ring 13 consists of a grooved ring 16 that is slidably mounted upon the shaft 3. The ring 16 is connected to the ring 13 by means of rods 17, which in turn are slidably disposed in bores 18 of the pulley 4. A yoke 19 is operatively connected to a manually controlled lever (not shown) by means of a link 22. Movement of the link 22 will cause the ring 13 to move so as to swing the blades 9. The rings 13 and 16 and the rods 17 are rotated with the pulley 4.

The blades 9 are held in any desired position by means of spring pressed plungers 23, which are slidably disposed in bores 24 of the pulley 4. The rods 17 are serrated at 25 and the ends of the plungers which engage with the rods are wedge-shaped, whereby the plunger prevents normal movement of the rods 17 in the bores 18. The plungers 23, however, will yield when the link 22 is manually actuated, whereby the rods 17 may be moved at will so as to swing the plates 9. The springs 26 which bear against the plungers 23 are held in place by means of screw plugs 27.

It will be noted from Figure 2 that each of the blades 9 is pivotally secured at each end. The inner ends of the blades 9 are pivotally held in place by means of the

shafts 10, while the outer ends of the blades are provided with trunnions 28, which are rotatably disposed in sockets 29 of the ring 30.

- 5 From the foregoing description of the various parts of the device, the operation thereof may be readily understood. As heretofore stated, the device can be readily applied to the fan-shaft 3 of the automobile and takes the place of the ordinary engine cooling fan.

Assume that it is winter time, and that the water in the radiator has become frozen. The operator can adjust the lever 22 so as 15 to swing the blades into a position which will prevent air from being drawn through the radiator. The engine will soon become heated when started, and will retain practically all of its heat, since the blades 9 are 20 not forcing air over the engine so as to cool the latter. The heated engine will quickly melt the ice in the radiator, whereby the circulation of water is once more started. In winter travel, it is often necessary for 25 the operator to place a cardboard over the front of the radiator, or have some device for preventing the air from entering the radiator, during the time the car is running. In the present device, the blades can 30 be swung so as to prevent air from passing into the radiator, whereby the engine will not be cooled to such a degree as to prevent the engine from operating efficiently. If desired, the blades can be swung so as to force 35 the air from the engine out through the radiator. This flexibility of control permits the driver to keep the heat of the en-

gine at any degree of temperature desired. The device is simple in construction, and can be readily attached to the fan shaft of an engine.

We claim:

1. A device of the type described comprising a housing adapted to be rotated, blades carried by said housing, said blades being adapted to rotate on their longitudinal axes, means for swinging said blades into any angle desired, means for locking said blades in adjusted position, and means connecting the outer ends of said blades together. 50

2. A device of the type described comprising a shaft, a housing mounted on said shaft, a plurality of blades carried by said housing, means securing the outer ends of said blades together, said blades being rotatably mounted in said housing and said means, rods slidably carried by said housing and being operatively connected to said blades, means for locking said rods in adjusted position, and common means for actuating said rods. 55

3. A motor fan comprising a shaft, a casing carried by said shaft, blades rotatably carried by said casing, arms secured to said blades, a ring having slots therein, the end of said arms slidably received in said slots, means for moving said ring whereby said blades are rotated on their longitudinal axes and means for locking said blade swinging means and a ring secured to the free ends 70 of said blades. 65

JOSEPH O. FORGETTE.
RICHARD LEGOIS.
